United States Patent Office.

T. E. SEXTON, OF WILMINGTON, DELAWARE.

Letters Patent No. 66,994, dated July 23, 1867; antedated July 18, 1867.

IMPROVED RAILROAD RAIL-COUPLING.

The Schedule referred to in these Letters Patent and making part of the same.

TO ALL WHOM IT MAY CONCERN:

Be it known that I, T. E. SEXTON, of Wilmington, New Castle county, Delaware, have invented an improved Rail-Coupling; and I do hereby declare the following to be a full, clear, and exact description of the same, reference being had to the accompanying drawing, and to the letters of reference marked thereon.

My invention consists of two plates lapped together and adapted and secured to the ends of two rails, substantially as described hereafter, so as to form a secure, unyielding coupling for the said rails. My invention further consists of two or more lips formed on one plate for underlapping and confining the folds of the other plate, as described hereafter.

In order to enable others skilled in the art to make and use my invention, I will now proceed to describe its construction and operation. On reference to the accompanying drawing, which forms a part of this specification—

Figure 1 is a side view of my improved rail-coupling.

Figure 2, a transverse section.

Figure 3, an inverted plan view.

Figures 4 and 5, views showing the two portions of the coupling separate from each other; and

Figure 6 a modification of the invention.

Similar letters refer to similar parts throughout the several views.

The improved coupling consists of two plates, A and A', the former being bent to the shape illustrated in fig. 4, and the latter to the form shown in fig. 5, the portion *a* of the plate A fitting in the space *b* between the folds *d* and *d'* of the plate A'. Two lips *e* are formed at the bent portion of the plate A', on or near each edge of the same, the lips being made by cutting the plate and bending the cut portions to the form represented in fig. 2, so as to underlap the folds of the plate A and bind them firmly against the plate A'. The portions *h* of both plates are bent to conform to the shape of the rails, and are secured thereto by two or more bolts, *i. e.* The ends of the two rails are thus firmly embraced by and between the two plates, which form a secure and unyielding coupling. Instead of the wide laps or folds already described, narrow folds similar to those shown in fig. 6 may be made in the plates, the lips *e* being unnecessary in this case.

I claim as my invention, and desire to secure by Letters Patent—

1. The two plates A and A', lapped together and adapted and secured to the ends of two rails, substantially as described, for the purpose specified.

2. The lips *e* on the plate A', arranged to underlap and confine the folds of the plate A, as set forth.

In testimony whereof I have signed my name to this specification in the presence of two subscribing witnesses.

T. E. SEXTON.
